INVENTOR.
Theodore HUTNIKOW
BY
George C. HERMANAS
ATTORNEY.

UNITED STATES PATENT OFFICE.

THEODORE HUTNIKOW, OF BROOKLYN, NEW YORK, ASSIGNOR TO VOICES INCORPORATED, OF NEWARK, NEW JERSEY, A CORPORATION OF DELAWARE.

VOICE FOR TOYS.

Application filed May 23, 1923. Serial No. 640,901.

This invention relates to improvements in sound devices for toys, particularly for dolls, and it is the principal object of my invention to provide a "ma-ma" or "pa-pa" voice and unarticulated sounds of unequal length by combining a tubular stem having a sound opening with the weighted disk and displacing the same within a second tube having a larger and a smaller opening.

Another object of my invention is to provide an articulating sound producing device of the type having a cylindrical bellows contained within a casing or housing, one end of the bellows wall being fixed to the casing while the weighted disc closes the other end of the bellows and in which the sound receiving tube carried by said disc having telescopic engagement within the relatively fixed tube at all times prevents angular tilting movement of the weighted disc. Another feature resides in the provision of means within the casing limiting the movement of the weighted disc to dis-tend the bellows, and thereby preventing undue strain on the flexible wall of the bellows at its fixed end.

A further object of the invention is the provision of an additional reed for the production of a continuous sound representing a baby's cries aside from the "pa-pa" or "ma-ma" voice.

A still further object of my invention is the provision of a novel construction which embodies strengthening means and perforated covers so as to provide a device which is reliable and efficient in use, comparatively easy to manufacture, and which is yet durable and lasting.

These and other objects of my invention will appear as the description proceeds, and will then be specifically pointed out in the appended claims.

In the accompanying drawing, forming a material part of this disclosure:

Figure 1 is a central longitudinal section through the device constructed according to the present invention on line 1—1 of Figure 2, with the bellows expanded.

Figure 2 is a top plan view of the device.

Figure 3 is a view similar to Figure 1 with the bellows collapsed.

Figure 4 is a top plan view of the

weighted disk and its stem, the latter in section on line 4—4 of Figure 5.

Figure 5 is a side view of weight and stem.

Figure 6 is a detail front view of the sound tube and parts connected therewith in section.

Figure 7 is a section on line 7—7 of Figure 6.

Figure 8 is a central section through a modified form of my device.

Figure 9 is a top plan view of the cover plate for the weight, and

Figure 10 is a section on line 10—10 of Figure 9.

A cylindrical casing 10, for instance a piece of mailing tube stock, has an inner partition 11 secured therein intermediate its ends and provided with a strengthening corrugation 12 for bracing the walls of the tube.

To this partition 11 is secured the lower end of a sound tube 13 provided with a comparatively large opening 14 and a smaller opening 15 in its side wall. The upper end of the tube 13 is secured in the cover plate 16 which is provided with a plurality of openings 17, and has a crimped or beaded outer flange 18.

The lower compartment 19 formed by the partition 11 contains a bellows 20, one end wall of which is formed by a weighted disc 21, while the other end formed by a plate 22 or disk 22 above the bottom plate 23 closing the lower end of the casing 10, and constructed in the same manner as cover 16.

Carried by the weighted disc 21 is a vertical tube 24. This tube is in communication through an opening in the disc 21 with the interior of the bellows. A plate 25 is secured to the upper face of the weight disc 21 and provided with an opening 26 for the passage of the tube or stem 24 which has an upper sound opening 27. The outer peripheral depending margin 28 of plate 25 is rolled to form a bead, and this is an important improvement over the known constructions of this kind as it acts somewhat like a ball bearing while sliding along the inner walls of the tube 10 and prevents a "sticking" which frequently occurs with the known plates having sharp edges.

A reed 29 of well known construction is provided within tube 24 and held therein by means of a cork ring 30.

It will be noted from reference to Figs. 1 and 3 of the drawing that the tube 24 on the disc 21 is at all times engaged within the fixed tube 13, thereby confining the disc 21 to a straight line axial movement within the casing and preventing angular tilting thereof. From the above description, it will be evident that in the movement of the disc 21 from the position shown in Fig. 1 to the position of Fig. 3, air is expelled under pressure from the bellows through the reed 29, the tube 24 constituting a sound receiving chamber and the emission of the sound through the opening 27 being interrupted by the wall of the fixed tube 13, the time periods of such sound emission being determined by the width of the openings 14 and 15 in the wall of the tube 13 with which the emission opening 27 successively cooperates. The movement of the disc 21 in the opposite direction to distend the bellows is definitely limited by the plate 11 fixed within the casing 10, thus preventing undue tensional strain on the flexible wall of the bellows and the possible separation of said bellows wall from the casing wall at its fixed end which would result in leakage of air.

In the modified form of my device illustrated in Figure 8, and additional tubular stem 31 is secured with its lower end to partition wall 11 and within this stem a reed 32 is held by means of a cork ring 33.

From the foregoing description taken in connection with the accompanying drawing, the advantages of my novel construction and its operation will be readily understood.

It is to be understood that the devices shown are merely illustrative and that such changes may be made when desired in the general arrangement and in the construction of the minor details as fall within the scope of the appended claims.

What I claim as new and desire to protect by Letters Patent is:

1. A sound producing device comprising a casing having an air chamber in one end thereof and a weighted gravity movable disc for causing a flow of air into and out of said chamber, a sound producing reed operated by the flow of air in the movement of said disc in one direction, a member fixed within said casing intermediate of its ends, a sound receiving chamber carried by said disc and movable through said fixed member, the wall of said chamber being provided with a sound emission opening, and a second relatively fixed member extending between said first named member and one end of the casing and having means cooperating with the sound emission opening in said chamber wall to interrupt the emission of sound therethrough.

2. A sound producer for toys comprising a bellows having a flexible tubular wall fixed at one of its ends, means closing said end of the bellows, a weighted disc closing the other end of the bellows and movable by gravity to collapse and distend the flexible wall of the bellows, a tube fixed with relation to said bellows and having spaced sound escape openings, a second tube carried by said disc communicating with the bellows chamber and slidably engaged with said fixed tube, a sound producing reed operated by the passage of air in the movement of said disc in one direction and communicating with the interior of the tube thereon, and the wall of said latter tube having a sound emission opening to cooperate with the sound escape openings of the fixed tube.

3. A sound producing device comprising a casing, a bellows within said casing having a weighty end wall movable by gravity to collapse and distend the bellows, a tube fixed with relation to said casing and having spaced sound escape openings, a second tube carried by said weighty bellows wall and slidably engaged with said fixed tube and communicating with the interior of the bellows, the wall of the latter tube having a sound emission opening to cooperate with the spaced sound escape openings of the fixed tube, and a sound producing reed mounted within the tube on said weighty bellows wall and operated by the passage of air in the movement of said member in one direction.

4. A sound producing device comprising a casing, a tubular bellows within said casing, a weighty gravity movable disc closing one end of said bellows, closure plates fixed on the opposite ends of the casing, an intermediate partition plate fixed within said casing and limiting the movement of said disc to distend the bellows, a fixed tube extending between said partition and one of the casing ends and having spaced sound escape openings, a second tube carried by said disc communicating with the bellows chamber and telescopically engaged within said fixed tube to thereby prevent angular tilting of the disc relative to its path of movement, the wall of the tube on said disc having a sound emission opening to cooperate with the spaced sound escape openings of the fixed tube, and a sound producing reed mounted within the tube on the bellows disc and operated by the flow of air in the movement of said disc in one direction.

5. A sound producer for toys comprising a hollow body, a corrugated and perforated partition wall dividing said body into an upper and a lower chamber, a bellows in the lower chamber of said body, a sound tube secured at its upper end to the cover of said body and depending therefrom, said sound tube having a large and a small lateral open-

ing, a weighted disc forming the upper end wall of said bellows, a recessed tube in said disc adapted to enter said sound tube through the perforation in said partition, a plate covering said weighted disc and having a beaded margin for preventing a binding or sticking of said weighted disc during its displacement within said body, a reed within said tube, a second tube on said partition wall, a reed in said second tube and cork rings for securing said reeds within their tubes.

In testimony whereof I have affixed my signature.

THEODORE HUTNIKOW.
